UNITED STATES PATENT OFFICE.

JACOB B. HOWELL, OF VETERAN, NEW YORK.

WHIFFLETREE.

SPECIFICATION forming part of Letters Patent No. 410,520, dated September 3, 1889.

Application filed June 5, 1889. Serial No. 313,119. (No model.)

To all whom it may concern:

Be it known that I, JACOB B. HOWELL, a citizen of the United States of America, residing at Veteran, in the county of Chemung 5 and State of New York, have invented certain new and useful Improvements in Whiffletrees for Spring-Tooth Harrows, of which the following is a specification, reference being had therein to the accompanying drawings.

10 My improvement in whiffletrees for spring-tooth harrows consists in its peculiar construction to enable the whiffletree to readily turn without being brought into contact with or striking the harrow, and in the peculiar 15 structure, combination, and arrangement of the parts, substantially as hereinafter shown and described.

In the accompanying drawings, Figure 1 is a plan view. Fig. 2 is a perspective of one of the 20 loops, and Fig. 3 is a side elevation thereof.

In constructing my whiffletree I provide the curved casting A, at either end thereof, with metallic loops B, secured thereto by means of nutted bolts C, for attaching the whiffletree to 25 the harrow. The casting A is also provided at the center of the segment with the enlargement or knob a, the metallic loop b being secured thereto by means of a nutted bolt.

Loop D is in like manner bolted to double- 30 tree h, the free ends of the loops being linked

together by means of ring e'. The loops e e and f f and the rings g g are of similar construction and arrangement, as is obvious, and thus the doubletree h and the singletrees F F are linked together. Thus constructed the 35 harrow may be readily turned in very small space without contact or striking of the parts, and a very complete and efficient whiffletree is produced.

Having thus fully described my invention, 40 what I claim, and desire to secure by Letters Patent, is—

The whiffletree consisting of the segmental casting or plate A, having at its ends pivoted loops B B, the loop b having its ends connected 45 to a central enlargement or knob a of the segmental plate A upon its rear or concave side, the doubletree h, having a central loop D, connected by a ring e' to the loop b of the segmental plate, and the singletrees F, having 50 loops f, connected by rings g with loops e at the ends of the doubletree h, substantially as set forth.

In testimony whereof I affix my signature in presence of two witnesses.

JACOB B. HOWELL.
